UNITED STATES PATENT OFFICE.

WILLIAM W. FORD, OF CARTIAGE, TENNESSEE.

DESIGN FOR A TOBACCO-PLUG.

SPECIFICATION forming part of Design No. 28,967, dated July 5, 1898.

Application filed June 1, 1896. Serial No. 593,927. Term of patent 14 years.

To all whom it may concern:

Be it known that I, WILLIAM W. FORD, a citizen of the United States, residing at Carthage, in the county of Smith and State of Tennessee, have invented a new and original Design for a Tobacco-Plug, of which the following is a specification.

This invention relates to a new and original design for a tobacco-plug; and it has for its object to provide a design of this character that shall be both useful and ornamental.

The leading feature of the design resides in a tobacco-plug comprising a tapering twisted body having a rounded strand circularly looped at one end of the body and having its opposite portions closely and spirally inter-twisted and decreasing in thickness, the terminals of the strand being doubled upon themselves and extended within the twist to produce a plaited blunt or rounded point for the plug.

In the drawings, Figure 1 is a perspective view of the tobacco-plug embodying the here-

in-described design. Fig. 2 is a side elevation thereof.

Referring to the drawings, the numeral 1 designates a tobacco-plug comprising a tapering twisted body having a rounded strand 2 circularly looped at one end of the body, as at 3. The opposite portions 4 of the strand are closely and spirally twisted together and decrease in thickness toward the point end of the body. The terminals of the strand 2 are doubled upon themselves and extended within the twist to produce a plaited blunt or 35 rounded point 6 for the plug.

What I claim is—

The design for a tobacco-plug herein shown and described.

In testimony that I claim the foregoing as 40 my own I have hereto affixed my signature in the presence of two witnesses.

WILLIAM W. FORD.
